UNITED STATES PATENT OFFICE.

IRENE M. CHILDS, OF LOS ANGELES, CALIFORNIA, ASSIGNOR OF ONE-HALF TO ELLA M. SHUTE, OF LOS ANGELES, CALIFORNIA.

TOY.

1,424,450.

Specification of Letters Patent.

Patented Aug. 1, 1922.

Application filed June 13, 1921. Serial No. 477,156.

To all whom it may concern:

Be it known that I, IRENE M. CHILDS, a citizen of the United States, and residing at Los Angeles, in the county of Los Angeles and State of California, have invented a new and useful Toy, of which the following is a specification.

This invention relates to devices used by children as well as by adults for passing time.

One of the objects of this invention is to provide a device in which a player may, by some skill, bring a traveling object to a certain goal.

Another object is to provide such a device with interfering means, eventually to be controlled by another player, to prevent the first traveling member or object from reaching its goal, though the first player may have properly operated the object.

Another object is to provide such a device with helping means, eventually to be controlled by another player, to prevent the interfering means from reaching its interfering position and thereby helping the first traveling member to reach its proper goal.

Another object is to provide side goals into which the first traveling member may be brought by the interfering means.

Other objects will appear from the following description and appended claims as well as from the accompanying drawings, in which—

Fig. 1 is a perspective view of a simple construction embodying the invention.

Fig. 2 is a perspective view of a slightly modified and simplified device.

Fig. 3 is a vertical midsectional view of a slightly modified form of the device.

Fig. 4 is a detail longitudinal midsectional view of an operating gun.

Fig. 5 is a vertical midsectional view of a slightly modified form of the device, the interfering members being guided through closed tubes terminating at an advanced point in the path of the traveling member.

Fig. 6 is a vertical midsectional view of a slightly modified form of the device, the inclined face being provided with grooves to guide the main ball in certain directions.

Fig. 7 is a grooved device similar to the illustration in Fig. 6, the bottom of the goal for the main ball being provided with means

to be operated by the interfering ball to bring the bottom in alignment with the bottom of the main grooves.

Fig. 8 is a detail fragmentary illustration of a trap door to be opened by the interfering ball.

Fig. 9 is a detail fragmentary illustration of tubes provided with interfering curves and pockets.

In Fig. 1, a base plate 10 is provided with a groove 11, in which a ball 12 may travel from the point 13 to the point 14. The point 13 may more properly be called the starting point, and the point 14 may more properly be called the goal. Another groove 15 is provided so as to cross the first groove 11, as indicated at 16 and 17, the groove 15 terminating at a separate and independent goal 18. A ball 19 may travel from the point 20 to the point 18 along the groove 15. Another groove 21 is provided so as to cross the groove 15, as indicated at 22. A ball 23 may travel from the point 24 to the point 25.

The ball 19 may more properly be called an interfering ball or member. The ball 23 may more properly be called a helping ball or member.

The ball 12 may normally easily reach the goal 14. The interfering ball or member 19 is operated to reach one of the crossings or intersections 16 or 17 to throw the ball 12 out of the groove 11. With a reasonable amount of skill the member 19 can be operated to eventually cause the member 12 to pass ahead of the member 19 into the goal 18. The ball or member 23 can, with a reasonable amount of skill, be operated to throw the member 19 out of the groove 15, eventually into the goal 25. The helping member 23 helps in this manner the member 12 to reach its goal at 14, since the interfering member 19 is prevented from reaching any of the intersections of the groove 15 with the groove 11 by such helping of the helping member. Another groove 26 is provided to allow another interfering member 27 to eventually cross the path of the traveling member 12. Another groove 28 is provided to allow another helping member 29 to eventually prevent the interfering member 27 from passing into the path of the traveling member 12, thereby helping the traveling member to reach its goal.

number of interfering and helping members with the required number of grooves can, of course, be provided.

To make this device an interesting toy or game, the several balls or members may be called certain names or made to represent certain things, as for instance, a couple trying to get to a church at 14; a parent trying to interfere; a friend of the couple trying to help the couple by stopping the interference of the parent; a constable, employed by the parent, trying to interfere with the couple, eventually to take the couple to a jail at 18; and a second friend helping to prevent the constable from reaching the couple before they can reach the church.

Other arrangements and instructions may easily be furnished with such a toy or game, as will easily be understood, without departing from the principle of the invention.

A slightly modified form, embodying the same principle, is illustrated in Fig. 2, instead of the curved groove 11 there is the straight groove 30, so that a traveling member may be operated to reach the goal 31; the interfering members may be operated to stop the traveling member at the points 32 or 33, when passed along the grooves 34 and 35; and, the helping members may be operated along the grooves 36 and 37 to stop the interfering members at the points 38 and 39.

Instead of open channels or grooves, tubes may as well be used without departing from the principle of the invention. While in open grooves, the operation of one party may easily be watched by the opposing party to operate the interfering member accordingly, eventually by throwing the interfering member improperly against the main traveling member; in closed channels or tubes, skill alone is the main factor, the interfering member is to be operated with just the proper velocity to reach an intersection to bring or give the desired results.

In Fig. 3, another slightly modified form is illustrated. An inclined surface is provided for the main traveling member, preferably in form of a hopper-shaped or conical receptacle. The main traveling member is operated on the face or surface of this receptacle or hollowed base 40 to wind its way to reach the goal 41, the traveling member being indicated at 42, and the path eventually taken by the traveling member is indicated at 43 with reference to the dotted lines. The traveling member may in this manner be given an exceedingly high velocity to circle several times before reaching its goal at 41, or it may be operated so slowly that the goal is reached in one circling or spiral movement. A losing goal is provided in the bottom of the hollowed base 40 as indicated at 44. If the traveling member

is not operated properly, it passes the proper or winning goal at 41 and drops into the losing goal at 44. A starting tube 45 is provided with a starting gun 46, by which the traveling member may receive any desired velocity. A funnel 47 is provided to allow the inserting of the traveling member into the starting tube near the gun. A channel 48 is provided so that an interfering member can be operated to drop into the hollowed base 40 at a point near the path of the traveling member on the inclined surface of the base. A cross tube or channel 49 is provided so that a helping member may be operated to stop the interfering member on the channel 48.

The starting gun is illustrated in detail in Fig. 4. The starting tube 45 is provided with a closed end 50, so that a spring 51 can be inserted between the end-plate 50 and a plunger 52. The plunger is connected to the rod 53, which is shouldered as indicated at 54 and provided with a handle as indicated at 55. When the plunger 52 is drawn back against the tension of the spring 51, a traveling member can be dropped through the funnel 47 into the starting tube 45 in front of the plunger, so that, on releasing of the handle 55, the plunger 52 and therewith the inserted traveling member is forced to move at a suitable or desired velocity in the tube 45. This starting velocity, received from the plunger and spring, is used to operate the traveling member at desired velocities, or in a desired manner over the inclined surface of the hollowed base 40.

A slightly modified form is illustrated in Fig. 5, the tube 56 for the interfering member being connected to the base 40 at a point near the path of the main traveling member close to the goal of the traveling member, so that the interfering member must not be operated until the main traveling member has nearly reached its goal, and eventually can only be reached at one certain point by the interfering member.

Guiding grooves 57 are provided in the slightly modified form illustrated in Fig. 6, so that the main traveling member can be dropped on the base to be guided along the grooves to finally reach its proper goal if not interfered with.

The grooves may, of course, be arranged closer than illustrated in Figs. 6 and 7, since a ball will easily follow the path of grooves for a long distance. In Fig. 7, the grooves 58 are illustrated in a closer relation, but the construction as a whole is the same as the hollowed base 40 in Fig. 6. A slight modification of the interfering means is, however, embodied in this illustration. The tube 56 for the interfering member terminates outside of the hollowed base 40 in a bent-end 57. An interfering member, dropping

into the bent-end 57, falls upon the lever 58 of the gate 59, thereby closing the gate. The gate 59 is normally of a width to allow the regular or main traveling member to drop 5 out of its path on the groove 58 down to rest on the normally open gate, this being the winning goal in this case, the gate forming a continuous groove when in closed position thereby causing the traveling member 10 to pass its winning goal.

In Fig. 8 is an illustration of a slightly modified gate, the gate forming in this case a trap door to be opened by the interfering member to prevent the traveling member 15 from continuing in its regular path in the grooves of the hollowed base. The interfering member, dropping into the bent-end 57 of the tube 56, falls upon the lever 60, lifting the lever 61 of the trap-door 62, 20 thereby opening the trap-door. This trap-door can be used in connection with any of the forms illustrated in Figs. 1, 3, 5, 6, 7 and even 2, as will easily be understood.

Traps, impediments, and obstacles are also 25 provided for the tubes, as illustrated in detail in Fig. 9. The tube 63 is provided with a trap or curved portion at 64, so that a ball, forced through the tube at a slow rate may stop within this portion 64 and 30 thereby fail to reach its proper goal or interfering point. On the other hand, on being forced through the tube at an exceeding rate of speed, the ball may pass into the extension trap, indicated at 65, thereby passing 35 its normal goal or interfering point at 66.

From the above it will easily be understood that all the several illustrations relate 40 to the same principle, namely to provide a path for a traveling member to reach a pre-determined goal when operated with a suitable amount of skill, having interfering means provided to prevent the first member 45 from reaching its goal when the interfering member is operated with a suitable amount of skill, and having helping means to prevent the interfering means from stopping the traveling member in its regular path.

Having thus described my invention, I 50 claim:

1. In a toy, in combination with traveling members, a base member forming guiding means for the said traveling members, a certain portion of the guiding means being of a continuous form terminating in a certain goal, another portion of the guiding means intersecting the first-named portion at a point before the goal, and extending to a point distant and separate from the first-named portion and goal, and another portion of the guiding means intersecting the second-named portion at a point before the intersection of the first two portions and extending to a point distinct from the other portions. 65
2. In a toy, in combination with traveling members, a base member having guiding means, a certain portion of the guiding means being of a continuous form terminating in a certain goal, another portion of the guiding means intersecting the first-named portion at a point before the goal and extending to a point distant and separate from the first-named portion and goal and another portion of the guiding means intersecting the second-named portion at a point before the intersection of the first two portions, and extending to a point distinct from the other portions, the said traveling members to be operated in the guiding means as interfering and helping members to one continuously traveling member. 70
3. In a toy, a base member having guiding means, a certain portion of the guiding means being of a continuous form terminating in a certain goal, another portion of the guiding means intersecting the first-named portion at a point before the goal, and extending to a point distant and separate from the first-named portion and goal, another portion of the guiding means intersecting the second-named portion before the intersection of the first two portions, and extending to a point distinct from the other portions, and traveling members adapted to be moved in the said guiding means as interfering and helping members to one continuously operating traveling member. 85
4. In a toy, traveling members, a base member forming guiding means for one of the traveling members, other guiding means in operative relation to the guiding means in the base member having an independent course and traversing the first-named guiding means so that a second traveling member may be operated to halt the first-operated traveling member, and other guiding means in operative relation to the guiding means for the second traveling member but normally in no operative relation to the guiding means for the first-named traveling member having an independent course and traversing the second-named guiding means adapted to serve a third traveling member to halt the second-named traveling member at a point distant from the path traveled by the first-named traveling member. 100
5. In testimony that I claim the foregoing as my invention I have signed my name in the presence of two subscribing witnesses. 105
